UNITED STATES PATENT OFFICE.

BENJAMIN F. MARTY, OF FRIANT, CALIFORNIA.

WELL PUMP.

Application filed June 22, 1925. Serial No. 38,768.

My invention relates to improvement in well pumps and the like wherein a plunger is reciprocated within a pump casing to draw water from a well and force said water upwardly to the surface.

The present invention is an improvement upon my former invention, patented April 14, 1925, Number 1,533,440, and consists of an improved construction and arrangement 10 of elements, the primary object being to provide an improved construction wherein the plunger actuating rod is effectually enclosed from the plunger to the top of the well to protect the same from the action of water 15 in the casing, and to afford a means for lubricating the plunger.

Another object is to provide an improved construction adapted to increase the capacity of the pump without increasing the size or 20 stroke of the plunger.

A further object is to provide an improved construction affording a more positive and efficient valve action.

A still further object is to provide an improved construction and arrangement of parts to facilitate the removal of the valve mechanism from the well and to avoid restricting the flow of water into the pump.

The invention resides in the particular 30 form and arrangement of parts disclosed in the drawings forming a part of the present specification wherein like characters of reference are used to designate similar parts throughout said specifications and drawings 35 and in which,

Fig. 1 is a vertical section of the lower 40 end of a pump casing showing in elevation the manner in which the plunger and valve mechanism are mounted therein.

Fig. 2 is a vertical section showing the construction of the plunger and valve mechanism.

Fig. 3 is a transverse section taken upon the line 3—3 of Fig. 2 in the direction indicated, parts being broken away to show the underlying structure.

Fig. 4 is a transverse section taken upon the line 4—4 of Fig. 2 in the direction indicated.

Referring to the drawings my improved pump will be seen, as in my former invention above referred to, to consist of a casing 1 having a reduced lower end portion 2 within which is mounted a cylinder 3. A valve cage 4 is seated upon a conical seat 6 formed in the bottom of the cylinder 3 and

an annulus 7 is seated upon a conical shoulder 8 formed between the reduced portion 2 and the main upper portion of the casing 1. Openings 9 and 10 in the bottom and top of 60 the cage 4 form communication between the well and interior of the cylinder 3 while openings 11 formed in the sides of the cage and matching with openings 12 formed in the cylinder afford communication between 65 the cage and cylinder and the lower end of the reduced casing portion 2. A plunger 14 is mounted for reciprocating movement within the cylinder, said plunger being operated by an actuating rod 16 extending upwardly through the annulus 7 to the top of 70 the well.

In my present invention I provide a casing 17 connected at its lower end to the annulus 7 and loosely enclosing the rod 16 from the 75 annulus to the top of the well. The casing 17 excludes water from the upper portion of the cylinder and protects the rod 16 from corrosion by the water above the cylinder, and at the same time affords a means whereby lubricant may be introduced into the cylinder to reduce wear and improve the efficiency of the pump. The casing forms a 80 vent communicating between the top of the cylinder and the atmosphere, thereby avoiding the forming of a vacuum above the plunger during its downward movement and thus permitting the use of a solid rod 16 in place of a tubular rod as in my former invention. In event there is any leakage into 85 the cylinder, past the plunger or otherwise, the water will be forced upwardly through the casing and thereby indicate that the pump should be overhauled.

In order to increase the efficiency and capacity of the pump I provide the annulus 7 with a plurality of relatively large openings 18 arranged annularly to communicate between the upper and lower portions of the casing 1 outside of the cylinder 3. The several openings 18 are arranged to be closed by means of a single annular valve plate 19 adapted to be lifted by the pressure of water from below during the downward stroke of the plunger 14 and thereby permit water to be forced upwardly through the openings into the upper portion of the casing and thence upwardly to the top of the well. A flange 21 is formed upon the casing 17 slightly above the annulus 7, and a spring 22 is mounted between the flange 21 and the valve plate 19 to normally hold the plate 100 105 110

seated upon the upper surface of the annulus and thereby prevent the return of water from the upper to the lower portion of the casing.

5 The casing 4 is provided with a conical seat 23 arranged to receive a valve 24 adapted to close the passage 9 into the well. The valve 24 is mounted upon a stem 26 the upper and lower ends of which are slidably 10 received in bearings 27 and 28 held in central position within the openings 9 and 10 by means of webs 29 and 31 connected to the opposite walls of the cage in the form of spiders whereby the bearings may be supported within the opening with the least 15 obstruction to the passage of water through the cage. A spring 32 is mounted between the upper side of the valve 24 and the webs 31 to normally hold the valve seated and 20 closing the passage from the well into the cylinder 3.

A threaded extension 33 is formed upon the bottom of the plunger 14, and a corresponding threaded recess 34 is formed in the 25 top of the cage 4 whereby the plunger may be caused to engage the cage and permit the cage and valve to be withdrawn from the well without removing the casing 1. The threaded recess 34 forms a continuation of 30 the passage 10 upwardly from the cage into the cylinder, and it will be noted that the opening thus afforded is relatively large and hence presents relatively little obstruction to the passage of water therewith.

35 In operation the plunger 14 is reciprocated within the cylinder 3 by any suitable mechanism. During each upward stroke, water is drawn upwardly past the valve 24 into the cylinder 3. During the succeeding downward stroke the water in the cylinder is forced through the openings 11 and 12 into the lower portion 2 of the casing 1, and thence upwardly past the valve plate 19 and 40 into the upper portion of the casing. At 45 each stroke of the plunger additional amounts of water are forced into the upper portion of the casing until the same is entirely filled, and thereafter each stroke will cause the displaced water to be delivered out 50 of the top of the well. By increasing the area of openings at the valves 19 and 24 the resistance to the passage of water is materially lessened and as a result the capacity 55 of the pump is increased over that of my former device above referred to without increasing the diameter or stroke of the plunger.

Having thus described my invention what I claim as new and desire to secure by Letters Patent is,

60 1. A well pump comprising a casing; a cylinder mounted within the lower end of the casing; valve means mounted within the bottom of the cylinder for admitting water 65 into the cylinder and casing; an annulus

mounted within the casing and engaging the upper end of the cylinder, said annulus having openings communicating between the lower and upper portions of the casing; a plunger mounted within the cylinder; an actuating rod connected to the plunger and extending upwardly through the annulus to the top of the well; a casing connected between the annulus and the top of the well and loosely enclosing the actuating rod; an annular valve plate mounted above the annulus and adapted to be seated thereon for closing the openings; a flange mounted upon the casing and spaced above the valve plate; and a spring mounted between the plate and 80 said flange to normally hold the plate seated upon the annulus to prevent the return of water from the upper to the lower portion of the cylinder.

2. A well pump comprising a casing having a reduced lower end portion; a cylinder mounted within the reduced portion and having openings communicating with the casing; an annulus seated upon the upper end of the reduced portion and engaging the upper end of the cylinder, said annulus having a plurality of annularly arranged openings communicating between the lower and upper portions of the casing; a valve cage seated within the bottom of the cylinder and having openings communicating between the well and the cylinder and casing; a valve mounted within the cage and adapted to permit the movement of water into the cylinder and casing and to prevent a return movement of the water into the well; a plunger mounted for reciprocating movement in the cylinder; an actuating rod connected to the plunger and extending upwardly through the annulus to the top of the well; a casing connected at its lower end to the annulus and loosely enclosing the rod; a valve plate mounted above the annulus and adapted to be seated thereon for closing the openings; and means connected between the rod enclosing casing and the plate for normally holding said plate seated upon the annulus to prevent the return of water from the upper portion to the lower portion of the cylinder.

3. A well pump comprising a casing having a reduced lower end portion; a cylinder mounted within the reduced portion and having openings communicating with the lower end of the casing; an annulus seated upon the upper end of the reduced portion and engaging the upper end of the cylinder, said annulus having a plurality of annularly arranged openings communicating between the upper and lower portions of the casing; a removable valve cage seated within the bottom of the cylinder and having openings communicating between the well and the cylinder and casing; a valve mounted within the cage and adapted to permit the move-

ment of water into the cylinder and casing and to prevent a return movement of the water into the well; a spring mounted in a cage for normally holding the valve seated; a plunger mounted for reciprocating movement in the cylinder; an actuating rod connected to the plunger and extending upwardly through the annulus to the top of the well; a casing connected at its lower end to the annulus and loosely enclosing the rod; a valve mounted in connection with the annulus and adapted to be seated thereon for closing the openings so as to prevent the return of water from the upper to the lower portion of the well; and a threaded extension formed upon the bottom of the plunger and adapted to engage a corresponding threaded recess formed in the top of the cage whereby the cage may be engaged and removed from the well.

4. A well pump comprising a casing having a reduced lower end portion; a cylinder mounted within the reduced portion and having openings communicating with the lower end of the casing; an annulus seated upon the upper end of the reduced portion of the casing and engaging the upper end of the cylinder, said annulus having a plurality of annularly arranged openings communicating between the upper and lower portions of the casing; a removable valve cage seated within the bottom of the cylinder and having openings communicating between the well and the cylinder and casing; a valve mounted within the cage and adapted to permit the movement of water into the cylinder and casing and to prevent a return movement of the water into the well; a spring mounted in the cage for normally holding the valve seated; a plunger mounted for reciprocating movement within the cylinder; an actuating rod connected to the plunger and extending upwardly through the annulus to the top of the well; a casing connected at its lower end to the annulus and loosely enclosing the actuating rod; a flange formed upon the casing at a point slightly above the annulus; an annular valve plate resting upon the annulus and adapted to close the openings therethrough; a spring mounted between the plate and the flange to normally keep the plate seated upon the annulus to prevent the return of water from the upper portion to the lower portion of the casing; and a threaded extension formed upon the bottom of the plunger and adapted to engage a corresponding threaded recess in the top of the cage whereby the cage may be engaged and removed from the well.

In witness whereof I hereunto set my signature.

BENJAMIN F. MARTY.
